UNITED STATES PATENT OFFICE.

CHARLES M. EARL, OF DETROIT, MICHIGAN.

DISPENSING DEVICE FOR CARBONATED BEVERAGES.

1,297,333.

Specification of Letters Patent. Patented Mar. 18, 1919.

Application filed April 1, 1918. Serial No. 225,908.

To all whom it may concern:

Be it known that I, CHARLES M. EARL, a citizen of the United States, residing at Detroit, in the county of Wayne and State of Michigan, have invented a new and useful Dispensing Device for Carbonated Beverages, of which the following is a specification.

This invention relates to dispensing devices for carbonated beverages, more particularly ginger ale.

It is the object of the invention to facilitate and expedite the dispensing of such highly carbonated beverages as ginger ale by providing means to quickly relieve the gas pressure under which such beverage is charged when stored in containers to reduce the effervescent tendency of the liquid when drawing it from the container into serving receptacles, and to accomplish this result by spreading the discharging agitated beverage in a thin film upon the walls of an aerating chamber so that the carbonaceous gas will be readily liberated to escape allowing the mixture to settle and liquefy preparatory to final discharge from said chamber.

In attaining this object, the invention contemplates associating a gas separating or aerating chamber in a unitary relation with a valve controlling delivery from the container thereto, said chamber having an outlet for the discharge of the beverage into serving receptacles, and the unit being adapted for direct connection to the container wherein the beverage is stored under gaseous pressure.

A preferred embodiment of the invention is illustrated in the accompanying drawing, wherein, Figure 1 is a view in side elevation of the dispensing device applied to a common form of beverage container.

Fig. 2 is a vertical sectional view of the device.

Fig. 3 is a sectional view, the plane of section cutting the gas separating chamber as indicated by line 3—3 of Fig. 1.

In these views the reference character 1 designates a valve and 2 the valve casing, the latter having its lower or inlet end screw-threaded, as indicated at 3 for connection with the outlet pipe 4 of a tank or beverage container 5. It is to be understood that the beverage within said container is under pressure of a carbonaceous gas and is

impregnated therewith. Any suitable type of valve will serve the purpose of the discharge from the container. Surmounting the valve casing 2 is a mixture aerating or separating chamber comprising a base 6 integral with said casing, a top 7, and a glass cylinder 8 clamped between said top and base by a plurality of bolts 9, the extremities of which peripherally engage said top and base exteriorly of the cylinder. The top 7 has a central upwardly embossed dome portion 10 in which are formed a series of outlets 11 for the escape of gas liberated within said separating chamber. The base 6 is formed with a liquid discharge spout 12, having the customary down-turned outlet. Between the cylinder 8 and the base and top, packing rings 13 are interposed to insure against leakage at the joints.

The upper or discharge end of the casing 2 is threaded for engagement with the lower end of a stand pipe 14 which rises centrally within the separating chamber and carries on the upper portion thereof a rotative discharge nozzle formed by a plurality of hollow arms 15 radiating from a collar 16 journaled on the pipe 14 and into which the inner ends of said arms are screw-threaded. The hollow arms communicate with an annular space 17 formed interiorly of the collar 16 and through said space and a series of passages 18 with the pipe 14. Each of the arms 15 is provided with a row of jet orifices 19 at one side thereof, the arrangement of said orifices in the several arms corresponding so that re-action of the discharging jets upon the nozzle will induce rotation thereof. An annular shoulder 20 upon the pipe supports the nozzle, and a nut 21 threaded upon a shouldered stud formed on the closed upper end of the pipe 14 and engaging the collar 16 holds the nozzle against axial displacement from said pipe.

In the use of the above described construction, when the valve 1 is opened, the pressure of gas in the containers 5 will force the contents thereof up through the pipe 14, and through the outlets 18 and space 17 into the arms 15, from which it will escape through the orifices 19. In leaving the nozzle arms the carbonated liquid will be thrown in a large number of small jets upon the cylinder 8, being uniformly distributed in the horizontal plane of said jets due to the rotation of the nozzle induced by the re-

action of the jets upon the arms. Thus the liquid flows down the interior surface of the cylinder 8 in the form of a thin film, and in this form the carbonaceous gas is readily 5 liberated and quickly escapes from the separating chamber by way of the outlets 11. Being thus freed of its gas, the beverage as it discharges through the spout 12 is free from any effervescent effect and may be 10 served at once.

What I claim is:

1. A beverage dispensing device comprising a gas separating chamber having separate gas and liquid outlets, and a liquid discharge member rotatively mounted therein for uniformly spreading the liquid upon the wall of said chamber.
2. A beverage dispensing device comprising a gas separating chamber having separate gas and liquid outlets, and a liquid discharge member mounted therein and rotatively actuatable by the re-action of the discharge for spreading the liquid upon the wall of said chamber.
3. A beverage dispensing device comprising a gas separating chamber having separate gas and liquid outlets, a liquid discharge nozzle therein comprising a plurality of radial arms having outlets in corresponding sides thereof, and a delivery pipe for

said nozzle upon which the latter is rotatively mounted.

4. A beverage dispensing device comprising a valve and a gas separating chamber comprising a base integral with the casing of said valve, a transparent cylinder, a top, and means clamping said cylinder between the base and top, the top and base respectively having gas and liquid outlets, and a valve controlling delivery to said 40 chamber.

5. A beverage dispensing device comprising a gas separating chamber having separate gas and liquid outlets, a pipe extending upwardly into said chamber for delivering a 45 carbonated beverage thereto, said pipe having a series of laterally opening outlets in its upper portion, and a discharge member journaled upon said pipe comprising a plurality of radial tubular arms having correspondingly directed jet openings and a hub carrying said arms, having radial passages aligned with the arms and opening into an annular space adjacent the upwardly extending delivery pipe and communicating 50 with the outlets of said pipe.

In testimony whereof I sign this specification.

CHARLES M. EARL.
